ANGLE DISK ROLLER

Wallace C. MacGregor, Chicago, Ill.

Application March 3, 1941, Serial No. 381,519

10 Claims. (Cl. 94—50)

This invention relates in general to a self-propelled machine for road, farm, and general land smoothing operation having a plurality of rotatable disks disposed on a transverse angular shaft, but rotatable in parallel planes extending longitudinally of the direction of travel of the machine.

An important object of the invention is in the provision of a plurality of smoothing disks mounted upon an angularly transverse or oblique shaft with the disks disposed on the shaft to extend parallel to the longitudinal axis of the machine.

A further object of the invention is in the provision of driving means for engaging a plurality of disks mounted obliquely but driven parallel to the longitudinal axis of the machine.

A still further object of the invention is in the provision of a self-propelled vehicle having front and rear drives, the front drive being turnable for steering, and the rear drive comprising a plurality of parallel but laterally offset disks arranged to rotate upon a shaft extending at an angle to the direction of movement of the vehicle.

A still further object of the invention is in the provision of a rotatable mounting for a disk upon a shaft at an angle to the direction of rotation of the disk.

Other and further objects of the invention will appear in the specification and will be apparent from the accompanying drawings in which,

Fig. 1 is a side elevation with parts in section of an angle disk roller in accordance with this invention;

Fig. 2 is a plan view with parts broken away and in section of the roller shown in Fig. 1;

Fig. 3 is a sectional detail of the angle disk mounting; and

Fig. 4 is a side view of one of the disks and its angular mounting.

In operating a road roller or a machine for smoothing the surface of the ground or other material, the provision of a cylindrical roller extending at right angles across a supporting frame does not have a maximum leveling or smoothing effect, because it rides directly transverse or normally to the movement of the frame and causes a corresponding movement thereof. If this cylinder is divided into a plurality of parallel disks, which are separately driven, they will have a greater leveling effect, and if the disks are located at an angle to the direction of movement of the machine itself, the smoothing effect of the disks is greatly increased. The present invention relates to the provision of a plurality of

similar disks arranged in offset or overlapping parallel relation to each other upon an axis which may be as much as 30 degrees inclined transversely of the side frames, but in which the 5 disks are separately driven from opposite sides thereof parallel to the longitudinal axis of the machine, and each of the disks is mounted for separate free rotation, although they are intended to have common driving means and to be rotated in unison.

Referring now more particularly to the drawings, a supporting frame 6, generally rectangular, is formed of channel-shaped or other suitable structural beams with a circular channeled frame 7 inserted at the front. In this circular frame, a turnable steering support is mounted, comprising a pair of opposite blocks 8 seated in the interior channel of the frame 7 and cross connected by a rigid bar 9. A shaft or axle 10 is mounted at its ends in the blocks 8 and carries driving cylinders or supporting traction rollers 11 which are attached to and rotatable with the shaft 10. A driving gear 12 is mounted on the shaft between the rollers, and a worm gear 13 meshes therewith for driving the rollers. The worm gear is mounted upon a shaft 14 which is located at the center of the circular frame 7 so that the entire assembly consisting of the blocks 8, the cross bar 9, and the rollers 11 may be rotated in either direction in the frame for steering.

To effect rotation of the steering rollers 11, a bracket 15 is attached to the cross bar 9, a link 16 is connected at one end to the bracket, and at the other end to an arm 17 at the end of a shaft 18, having a beveled gear 19 at its upper end meshing with a beveled gear 5 at one end of a steering post 4 which has a steering wheel 3 at the other end for rotating it. By turning the 40 wheel in one direction or the other, the steering rollers 11 are inclined in a corresponding direction in the frame 7 to effect a steering movement of the machine.

The angle disk construction is mounted near one end, usually the rear, of the frame 6, by means of upright shafts or angle bearing supports 20 (see Fig. 3) secured to the sides of the opposite side frames and each having an inclined opening 21 for receiving the end of a shaft or bar 22 which is therefore set at a fixed angle transversely of the frame. Disposed upon the bar fitting close together to entirely fill the space between the bearing supports 20 are a plurality of bearing members 23, each having an angular bore or hole 24 extending centrally

therethrough upon the same angle that the bar 22 is mounted in the frame. The outer surface of the mounting 23 is circular and is less in diameter than the surface of the bearings 20 in contact therewith so that the bearing members 23 are more firmly in position along the bar 22. A roller disc 25 is rotatably mounted on each of the bearing members 23, all of the rollers being the same size and overlapping each other the same amount, and of a width or thickness the same as the mountings 23 so that the rollers are also firmly mounted upon the bearing members and are retained in relative position by them and the end bearing members 20 which are engaged by them. Each roller 25 is therefore separately mounted upon its bearing but fits closely with respect to the adjacent roller so that no dirt or other foreign material is likely to pass between the rollers or the bearings.

To rotate the rollers 25, a pair of contact rolls 26 are mounted one at each side of the assembled rollers, each driving roll being mounted upon end arms 27 pivoted above the rollers 25 upon a cross-shaft 28 substantially overlying the bar 22, the cross-shaft being mounted at its ends in bearing supports 29 secured to the opposite sides of the supporting frames 6. The arms 27 are loosely connected to the shaft 28 which is connected to each of the drive rollers by a driving sprocket and chain connection 30 which extends to a shaft 31 upon which each of the rolls is mounted. Preferably the outer portion or surface of each roll has a suitable fibrous rubber or composition coating which engages the opposite angular edges of the discs for rotating them. The rolls are maintained in contact with the roller disks 25 by springs 32 connected between the adjacent arms 27 of opposite rollers at the ends thereof.

The cross-shaft 28 is driven in any suitable manner, as by a gear 33 and pinion 34 connection with a drive-shaft 35. The drive-shaft is rotated in either direction by a driving chain connection 36 with an engine 37 of the automotive type having a transmission gearing in a gear case 38 operated by a shift lever 39 and having a cooling radiator 40 and an air circulating fan 41.

This engine is mounted or supported upon a frame or platform 41 raised above the frame 6 and held rigidly in place by supports 42, 43 fixed therebetween. An operator or attendant may ride upon the platform where the steering wheel 3, the motor 37 and its controls are closely adjacent.

Near the engine driving connection, the shaft 35 may be supported by a bearing brace 44 extending from and secured to the platform 41. At its other end, the shaft is supported by a hollow casing 45 for receiving the upper end of pinion shaft 14, the casing being fixed to the platform 41 at the bottom, and having a cap 46 at the top enclosing meshing bevel gears 47 and 48 secured to shafts 14 and 35 respectively. Bevel gears 33 and 34 at the other end of the drive shaft may also be enclosed by a casing 49.

In turning the steering rollers 11, it is necessary also to turn the gears 12 and 13 with the rollers 11 and if these gears are enclosed in the casing 50, the casing must also turn with the gears and relatively to the shaft supporting casing 45. For this purpose, the two casings are formed with relatively telescoping portions 51 and 52 which extend one within the other below the attachment of the upper casing to the plat-

form 41, the telescoping portions being concentric with the axis of the shaft 14 so that they rotate freely upon the fixed casing extension 52 when the front supporting rollers 11 are turned in either direction for steering.

With this construction, the same motor will drive the steering rollers 11, and also the angle drive rollers 25. If desired, either the front or the back rollers could be connected to the driving shaft by separate clutch connections without involving invention and which are not shown. The driving rollers both front and back are shown with smooth surfaces but they may be either grooved or ribbed to provide a better traction without materially affecting the operation of the machine in general or the driving rolls 26 in particular. By maintaining a firm but resilient contact of the driving rolls with the rollers 25, each of these rolls is engaged both at the front and at the back and a leveling rotation of the rollers 25 is insured.

I claim:

1. An angle-drive road roller having a frame, a plurality of rollers mounted in parallel planes lengthwise of the frame and upon a common axis obliquely transverse of the frame, and common driving means separately engaging the outer edges of the rollers to rotate them.

2. In an angle drive roller machine, a frame, a plurality of rollers separately mounted upon a common axis extending obliquely transverse of the frame, the rollers being rotatable at an angle to said axis, and front and rear driving means each commonly engaging the edges of the rollers at the front and rear thereof for rotating them.

3. In an angle drive roller machine, a frame, a plurality of rollers, a common axis for the rollers extending obliquely transverse of the frame with the rollers separately mounted at an angle thereto so that the rollers overlap at front and rear, and a common driving means also extending obliquely transverse of the frame and engaging the edges of the overlapping portions of the rollers to rotate them.

4. A road or surface roller, comprising a frame, a plurality of parallel rollers mounted upon a common shaft extending obliquely transverse of the frame, the rollers extending and rotatable in planes lengthwise of the frame and each overlapping the next roller, a common rotatable means engaging the projecting edges of all of the rollers to drive them, traction steering roller means at one end of the frame, and common driving means for the oblique and steering rollers.

5. In a roller drive machine, a frame having a circular portion at one end, a traction steering roller mounted to turn for steering in the circular portion about a connected drive shaft extending upwardly therefrom, an angle drive comprising a plurality of rollers having a common axis extending obliquely transverse of the frame, the angle drive rollers being at an angle to the axis, parallel to each other, and overlapping longitudinally of the frame, a pressure drive roll extending obliquely to resiliently engage the edges of the overlapping rollers for rotating them, and driving means extending to said drive shaft and to said roll for operating them at the same time.

6. In a roller drive machine, a plurality of rollers mounted at an angle for separate rotation upon an obliquely transverse axis and overlapping at front and rear, driving rolls to engage the overlapping portions at opposite sides of the rollers, arms on which the rolls are mounted, a common driven shaft parallel to said axis upon

which the arms are pivoted, driving means extending from the shaft to each roll, and resilient means for drawing the rolls together against opposite portions of the rollers.

7. In a roller drive machine, a frame, an angle drive thereon adjacent one end comprising a plurality of parallel rollers extending lengthwise of the frame but mounted for separate rotation on an axis obliquely transverse to the frame and in overlapping relation to each other, drive rolls engaging the rollers to rotate them, pressure means for applying the rolls to engage the separate rollers, steering traction rollers adjacent the other end of the frame, a circular frame portion in which the traction rollers are rotatable about a vertical axis for steering, a drive shaft extending along said vertical axis and connected to the traction rollers for positively rotating them, means for rotating the steering rollers about said axis for steering, a common drive means connected to the vertical drive shaft and to said drive rolls for actuating the machine from both ends of the frame.

8. In a roller drive machine, a frame, a plurality of rollers mounted for separate rotation at an angle upon an axis obliquely transverse to the frame at the rear thereof, pressure driving means for separately engaging each roller, a pair of tractive steering rollers at the front of the frame, a circular frame portion and means for mounting the steering rollers to turn about a vertical axis therein for steering, a drive shaft located upon the said vertical axis and having worm and pinion drives with the steering rollers, and means for mounting the worm and pinion drive to rotate with the rollers in their steering movement.

9. In a roller drive machine, a frame, a plurality of rollers mounted for separate rotation upon an axis obliquely transverse to the frame at one end thereof, common pressure driving 40

means for separately engaging each of the rollers, steering rollers at the other end of the frame, a circular frame portion in which the steering rollers are mounted about a central vertical axis for steering, a driving shaft located upon the said vertical axis, a worm and pinion drive between the shaft and the steering rollers, a casing for the shaft and said drive, the lower portion of the casing being rotatable with the steering rollers 10 in their steering movement, the upper portion of the casing being fixed to the frame and power means connected to the upper end of the shaft for rotating it.

10. In a roller drive machine, a frame having 15 a circular portion at one end and an operating platform placed above the frame, a plurality of driving rollers separately mounted upon the axis obliquely transverse to the frame at the other end having a common pressure driving member 20 which engages each roller, a pair of steering rollers spaced apart at the center and having a common shaft for rotating them in the circular portion of the frame about a central axis for steering, a driving shaft located upon the vertical axis and extending upwardly through the platform, a driving connection between said shaft and the roller shaft, a two part casing, one portion enclosing the upper end of the shaft and secured to the platform but extending below it, 25 the other part telescoping with the extending portion below the platform and rotatable thereon to enclose the driving connection between the shafts and rotatable with the rollers in their steering movement, means for rotating the steering rollers 30 including a steering wheel located at the top of the platform and a driving motor also mounted on the platform for engaging the upper end of the driving shaft.

WALLACE C. MACGREGOR.
